MEDICINE CABINET

Paul F. Simpson, Washington, Conn., assignor to
 The Autoyre Company, Incorporated, Oakville,
 Conn., a corporation of Connecticut

Application September 11, 1946, Serial No. 696,274

6 Claims. (Cl. 312—329)

1

This invention relates to cabinets formed of sheet metal, more particularly to sheet metal medicine cabinets adapted either for wall mounting or flush mounting, and the invention has for an object the provision of low-cost medicine cabinet structures which are attractive in appearance and are of rugged construction.

Various types of medicine cabinets constructed either in whole or in part of wood or sheet metal and including mirror doors have heretofore been proposed and certain of such prior structures have been largely satisfactory for the purposes intended in so far as appearance and utility are concerned. Such satisfactory medicine cabinet constructions, however, have heretofore been available only at excessively high prices, and prior attempts to reduce the cost of such cabinets have resulted either in flimsy and unsatisfactory mechanical constructions or in an unattractive appearance.

The present demand for so-called low cost housing of a type which maintains the conveniences and attractiveness of higher cost housing units has necessitated the provision of various types of fixtures, including medicine cabinets, of a type heretofore unavailable, and accordingly it is a further object of this invention to provide a medicine cabinet having the appearance of an expensive unit but which may be manufactured in large quantities at low cost and which will be of a strong and rugged construction.

In carrying out the invention in one form I provide a sheet metal body portion including a rear wall from which extend top and bottom walls respectively terminating at their forward edges in upwardly and downwardly extending vertical flanges respectively, the vertical flanges terminating in rearwardly extending flanges spaced from the top and bottom walls. Also extending forwardly from the rear wall are side walls which project beyond the vertical flanges of the top and bottom walls and terminate in rearwardly curved flanges forming vertically extending hollow posts on opposite sides of the opening defined by the top, bottom and side walls.

A door is hingedly disposed between the hollow posts and supported on the vertical flanges with the outer surface of the door substantially flush with the forward edges of the posts and the inner surface of the door overlying the vertical flanges when the door is in closed position. More specifically, the height of the vertical posts exceeds the distance between the top and bottom walls by the height of the vertically extending

flanges, and the rearwardly extending flanges associated with the top and bottom walls include integral end portions shaped to conform to the cross section of the vertical posts so as to overlie the upper and lower ends of these posts. One of the vertical flanges associated with the top and bottom walls of the cabinet body portion is provided with a slot extending transversely of the front face of the cabinet, and a stop member hingedly connected to the inner surface of the door extends through and is slideable along the slot during opening and closing movement of the door, the stop member having a portion thereon engageable with one end of the slot to limit the opening movement of the door.

For a more complete understanding of the invention, reference will now be had to the drawings in which:

Fig. 1 is a perspective view of a medicine cabinet construction embodying the present invention;

Fig. 2 is a front elevational view of the cabinet shown in Fig. 1;

Fig. 3 is a top plan view thereof;

Fig. 4 is a fragmentary plan view showing one upper corner of the cabinet on a somewhat larger scale, a portion of the cabinet and the door being broken away in order to show the hinge construction;

Fig. 5 is a fragmentary perspective view showing the cabinet with the door in partially open position so as to illustrate stop means associated with the door;

Fig. 6 is a fragmentary perspective view of one corner of the door;

Fig. 7 is a detail sectional view taken substantially along the line 7—7 of Fig. 5;

Fig. 8 is a plan view of a sheet metal blank from which the body portion of the medicine cabinet shown in Fig. 1 may be formed;

Fig. 9 is a plan view on a somewhat smaller scale showing another form of blank from which the side walls and posts of the medicine cabinet constituting another embodiment of the invention may be formed;

Fig. 10 is a plan view of a blank for forming the back wall and the top and bottom walls of the cabinet construction utilizing the blank of Fig. 9; and

Fig. 11 is an exploded perspective view showing the cabinet body construction formed from the blanks illustrated in Figs. 9 and 10.

Referring now to Figs. 1 to 8, inclusive, of the drawing, the invention is shown as embodied in a medicine cabinet 12 comprising a body portion including a rear wall 13 from which extend

top and bottom walls 14 and 15 each of which terminates in vertically extending flanges 16 and 17 respectively. Extending rearwardly from the vertical flanges 16 and 17 are suitable flanges 18 and 19, respectively, which extend substantially parallel to the top and bottom walls 14 and 15 in spaced relation thereto, each of the flanges 18 and 19 having suitably shaped end portions 20 the purpose of which will be more fully described hereinafter, and each of the flanges 18 and 19 terminates in a flange 21 and 22, respectively, which latter flanges respectively extend downwardly and upwardly toward the top and bottom walls, as shown best in Fig. 5 in connection with the flange 21 at the top of the cabinet.

Likewise extending forwardly from the rear wall 13 are the side walls 23, which side walls extend forwardly beyond the front edges of the top and bottom walls and terminate in rearwardly curved flanges so as to form vertical hollow posts 24 at each side of the opening defined by the top, bottom and side walls of the cabinet. The portions of the side walls which form the hollow posts 24 are of greater height than the distance between the top and bottom walls 14 and 15 by a distance equal to the height of the vertical flanges 16 and 17, so that the end portions 20 of the rearwardly extending flanges 18 and 19 overlie and engage the top and bottom edges of the post 24, each of these top and bottom edges being provided with suitable tabs 25 which may be bent inwardly and welded to the portions 20 on the flanges 18 and 19 so as to form a rigid structure. As shown in Fig. 8, the top wall 14 is provided at its opposite ends with flanges 26 which may be bent downwardly to engage in inner surfaces of the side walls 23 and which may be welded to the side walls when the cabinet body is formed. Likewise, the bottom edge of each of the side walls 23 is provided with a flange 27 which may be turned inwardly to engage the undersurface of the bottom wall 15 and may be welded thereto. Suitable additional tabs 28 formed adjacent the upper and lower ends of the portions 24 which form the vertical posts are provided, which tabs 28 are adapted to be bent inwardly behind the flanges 16 and 17 and welded thereto, as shown best in Fig. 8, so as further to strengthen the body portion of the cabinet. Thus it will be seen that I have provided a sheet metal body portion for the cabinet which may be formed from a single blank of sheet metal by means of simple bending and forming operations, and by means of a few simple welding operations a strong and rugged cabinet body portion having an attractive appearance is obtained.

Although various types of door structures may be provided I preferably provide a mirror type of door structure 30 which comprises a main frame portion and a pair of cooperating upper and lower cap members. The main frame portion of the door is formed of sheet metal and comprises a rear wall 31 which terminates at its opposite vertical edges in a forwardly extending flange 32, the forward edge of which terminates in an inwardly extending flange 33. The mirror 34 (Fig. 5) is adapted to be positioned in front of the main frame within the flanges 32 and 33, suitable spacing members being provided so as to hold the front surface of the mirror at the two vertical edges thereof in contact with the front flanges 33, and suitable U-shaped cap members 35 may then be snapped into position at the upper and lower ends of the main frame to complete the door structure. Each of the cap

members 35 includes a front flange 36 which engages the front surface of the mirror 34 and a rear flange 37, which is provided with suitable longitudinal corrugations 38 cooperating with similar corrugations 39 in the rear wall 31 of the main frame member to lock the cap members in position on the upper and lower edges of the door.

It will be observed that the door structure thus provided is of sufficient height to overlie the vertical flanges 16 and 17 of the cabinet body when the door is in its closed position and the front face of the door lies substantially flush with the front edges of the vertical posts 24 so that the door is nested therebetween.

In order to support the door 30 for swinging movement with respect to the cabinet body, suitable hinge means are provided for supporting the door on the upper and lower flanges 16 and 17 while substantially concealing the hinges. As shown best in Figs. 4, 5 and 6, the hinge structure comprises a first hinge member 40 which extends along the rear face of the flange 16 and through a suitable aperture 41 in this flange, the extending end of the strip 40 terminating in a hinge loop 42. The second hinge member 43 extends along the inner surface of the door frame 31 and terminates in a hinge loop similar to the hinge loop 42. The rear wall 31 of the door frame and the end flange 32 at the hinge side of the door are provided with an aperture 44 through which the strip 40 and the hinge loop 42 may extend so as to be brought into alignment with the loop on the hinge member 43, the two loops accommodating a suitable hinge pin 45 whereby the door 30 is supported in swinging relation, the upper and lower hinge constructions being substantially identical and only the upper hinge construction being shown in Figs. 4, 5 and 6.

In order to limit the swinging movement of the door from the closed position shown in Figs. 1 to 4, inclusive, a combined door closing and stop means is provided, which means is shown best in Figs. 5 and 7. The detailed construction of this combined closing and stop means, in so far as its closing function is concerned, forms no part of the present invention but is described and broadly claimed in the copending application of Roy S. Sanford and Paul F. Simpson Serial No. 200,619, filed December 13, 1950 and entitled Door Closure, said copending application being a continuation of application Serial No. 696,232 filed September 11, 1946, now abandoned. As shown best in Figs. 5 and 7, this closer and stop means consists of a link 46 one end of which extends through a suitable slot 47 in the vertical flange 16 of the cabinet body, and terminates in an enlarged end portion 48 disposed rearwardly of the flange 16. At its opposite end the link 46 is provided with a loop 49 for receiving a pin 50 which is confined between suitable indentations 51 and 52 in the rear wall 31 of the door frame and the rear flange 37 of the cap 35 respectively. In order to assemble the link 46 in proper relation to the cabinet body and the door, the enlarged end 48 of the link 46 is first inserted through the slot 47 by turning the link approximately 90° from the position shown in Fig. 5. The loop 49 on the opposite end of the link is then inserted through the aperture 53 in the flange 37 of the door cap 35 and the pin 50 inserted through the loop 49. The pin 50 is then positioned in the indentation 52 and the cap 35 placed in position over the upper end of the door and forced downwardly, the pin moving along the indentation 51 in the rear wall 31 of the door frame. The assembled

position of the pin 50 relative to the link 46 and the door structure is shown best in Fig. 7.

It will be observed that as the door swings between its open and closed positions the enlarged end 48 of the link moves within the housing formed by the flanges 16, 18 and 21 (Fig. 5) and the body of the link 46 moves through the slot 47. As the door approaches its outermost position the enlarged end 48 thereof approaches the end of the slot 47 and engagement of this enlarged end 48 with the end of the slot determines the maximum open position of the door.

Although the one-piece construction of the cabinet body illustrated in Figs. 1 to 8, inclusive, is preferable from many standpoints, it will be understood that similarly constructed and shaped cabinet bodies may be formed from two or more sheet metal blanks, and in Figs. 9, 10 and 11 a modified construction is shown wherein the blank 55 of Fig. 9, when shaped and slit as shown therein, may be formed to provide the front frame structure and side walls of the cabinet as shown best in Fig. 11. Thus the blank 55 includes the side wall portions 56 terminating in inwardly extending flanges 57 at the rear ends thereof and having similar inwardly extending flanges 58 at the bottom edges. At the front edge of each side wall 56 is a rearwardly curved flange which forms the hollow vertical posts 59, the upper and lower ends of which are closed by a rearwardly extending flange 60, the forward end of which is notched, as shown, and respectively provided with upwardly and downwardly extending flanges 61. Cooperating with the portion of the cabinet body formed from the blank 55 is a cabinet portion formed from the blank 62 shown in Fig. 10. This blank includes a rear wall portion 63 from which extend top and bottom wall portions 64 and 65 respectively, each of which terminates in a vertically extending flange 66 and 67, the top wall 64 having downwardly extending end flanges 68 as shown. When the blank 62 is formed as shown in Fig. 11, it may be assembled with the portion formed from the blank 55 so as to form a cabinet body structure embodying the present invention. When so assembled the flanges 66 and 67 engage the rear surfaces of the vertically extending flanges 61 and may be welded thereto, the flanges 57 on the side walls 56 similarly engaging and being welded to the rear wall 63. Likewise, the flanges 68 engage the inner surface of the side walls 56 at the upper ends thereof and the flanges 58 engage the undersurface of the bottom wall 65.

Upon completion of the various welding operations indicated a strong and rugged cabinet body portion is obtained having the same general configuration as the one-piece body portion formed from the blank of Fig. 8. Although the required slots and apertures in the vertical flanges 61 of the embodiment of the invention shown in Figs. 9 to 11, inclusive, have not been illustrated, it will be apparent that these flanges may be formed in the same manner as the vertical flanges 16 and 17 to provide for proper hinging of a door relative to the cabinet body and for association therewith of the stop means heretofore explained in connection with Fig. 5.

It will likewise be understood that the rear wall in either embodiment of the invention may be provided with suitable apertures to permit hanging of the cabinet body on the wall when wall mounting of the cabinet is desired, and the side walls in each case may be provided with suitable

projections for supporting glass or similar shelves thereon.

While I have shown particular embodiments of my invention, it will be understood of course that I do not wish to be limited thereto since many modifications may be made, and I, therefore, contemplate by the appended claims to cover any such modifications as fall within the true spirit and scope of my invention.

Having thus described my invention, what I claim and desire to secure by Letters Patent is:

1. A sheet metal medicine cabinet comprising a rear wall, a top wall extending forwardly from said rear wall and terminating in an upwardly extending flange, said upwardly extending flange terminating in a first rearwardly extending flange spaced from said top wall, a bottom wall extending forwardly from said rear wall and terminating in a downwardly extending flange, said downwardly extending flange terminating in a second rearwardly extending flange spaced from said bottom wall, side walls extending forwardly from said rear wall and beyond said upwardly and downwardly extending flanges of said top and bottom walls, said side walls terminating in outwardly and rearwardly extending flanges forming vertically extending posts on opposite sides of the opening defined by said top, bottom and side walls, a door hingedly supported between said hollow posts with the outer surface of said door substantially flush with the forward edges of said posts when said door is in closed position, and portions integral with and respectively coplanar with said first and second rearwardly extending flanges secured to and closing the ends of said posts.

2. A sheet metal medicine cabinet comprising a rear wall, a top wall extending forwardly from said rear wall and terminating in an upwardly extending flange, said upwardly extending flange terminating in a rearwardly extending flange spaced from said top wall, a bottom wall extending forwardly from said rear wall and terminating in a downwardly extending flange, said downwardly extending flange terminating in a rearwardly extending flange spaced from said bottom wall, and side walls extending forwardly from said rear wall and beyond said upwardly and downwardly extending flanges of said top and bottom walls, said side walls terminating in outwardly and rearwardly extending flanges forming vertically extending hollow posts on opposite sides of the opening defined by said top, bottom and side walls, the height of said posts exceeding the distance between said top and bottom walls by the height of said upwardly and downwardly extending flanges, said rearwardly extending flanges on said top and bottom walls having coplanar portions on the opposed ends thereof shaped to conform to the cross section of said posts overlying the upper and lower ends of said posts and secured thereto.

3. A one-piece sheet metal medicine cabinet formed from a single, sheet metal blank comprising a rear wall, top, bottom and side walls integral with said rear wall and extending forwardly therefrom, and flanges on the transverse edges of some of said forwardly extending walls extending at right angles thereto to overlap a surface of the adjacent walls for securement thereto to form a rigid frame, said top and bottom walls each having a flange at the forward edge thereof extending substantially vertically outward from said frame and terminating in an integral rearwardly extending flange, each of said side

walls extending forwardly of said forward edges of said top and bottom walls and having at the forward edge thereof an integral outwardly and rearwardly extending flange forming a vertically extending post, the height of said posts exceeding the distance between said top and bottom walls by the height of said vertically extending flanges on said top and bottom walls, said rearwardly extending flanges on said top and bottom walls having integral end portions shaped to conform to the cross section of said posts and overlying the upper and lower ends of said posts for securing thereto.

4. A one-piece sheet metal cabinet formed from a single, sheet metal blank comprising a pair of parallel side walls, each of said side walls having at the forward edge thereof an integral outwardly and rearwardly extending flange forming a vertically extending post, parallel top and bottom frame members integral with the forwardly extending portions of said flanges bridging said posts at the top and bottom thereof, said frame members having end portions shaped to the contour of the cross section of said posts for securing thereto to close the ends thereof, and outwardly and vertically extending flange members integral with said frame members in a plane spaced inwardly from the forward edge of said side walls providing a recess in the forward portion of said cabinet between said posts to receive a cabinet door.

5. A sheet metal medicine cabinet comprising a rear wall, a top wall extending forwardly from said rear wall and terminating in an upwardly extending flange, said upwardly extending flange terminating in a first rearwardly extending flange spaced from said top wall, a bottom wall extending forwardly from said rear wall and terminating in a downwardly extending flange, said downwardly extending flange terminating in a second rearwardly extending flange spaced from said bottom wall, side walls extending forwardly from said rear wall and beyond said upwardly and downwardly extending flanges of said top and bottom walls, said side walls terminating in outwardly and rearwardly extending flanges forming vertically extending posts on opposite sides of the opening defined by said top, bottom and side walls, a door hingedly supported between said hollow posts with the outer surface of said door sub-

stantially flush with the forward edges of said posts and the top and bottom thereof substantially flush with said first and second rearwardly extending flanges when said door is in closed position, and portions integral and respectively coplanar with said first and second rearwardly extending flanges secured to and closing the ends of said posts.

6. A sheet metal medicine cabinet comprising a rear wall, a top wall extending forwardly from said rear wall and terminating in an upwardly extending flange, said upwardly extending flange terminating in a rearwardly extending flange spaced from said top wall, a bottom wall extending forwardly from said rear wall and terminating in a downwardly extending flange, said downwardly extending flange terminating in a rearwardly extending flange spaced from said bottom wall, and a side wall extending forwardly from each side of said rear wall to a fold line forwardly of said upwardly and downwardly extending flanges and there bent outwardly and rearwardly forming vertically extending hollow posts on opposite sides of the opening defined by said top, bottom and side walls, the height of said posts being substantially equal to the distance between said top and bottom rearwardly extending flanges, said flanges being integral with said side walls, and the rearwardly extending flanges on said top and bottom walls having coplanar portions on the opposite ends thereof shaped to conform to the cross sections of said posts overlying the upper and lower ends of said posts and secured thereto.
